UNITED STATES PATENT OFFICE.

WILLIAM B. RUNYAN, OF DAYTON, OHIO, ASSIGNOR TO THE DAYTON MALLEABLE IRON COMPANY, OF DAYTON, OHIO, A CORPORATION OF OHIO.

MELTING FURNACE.

Application filed January 9, 1924. Serial No. 685,188.

This invention relates to furnaces, and more particularly to an improved type of melting furnace for use in the melting of iron, and the like.

5 One of the principal objects of the invention is to provide an improved type of melting furnace, which is particularly adapted for the utilization of powdered coal as a fuel.

10 Other objects and advantages of the invention will be apparent from the description thereof set out below, when taken in connection with accompanying drawing.

In the drawing in which like characters 15 of reference designate like parts throughout the several views thereof,

Fig. 1 is a horizontal sectional view, of a furnace constructed in accordance with this invention, the view being substantially 20 along the line 1—1 of Fig. 2.

Fig. 2 is a vertical sectional view through the form of furnace shown in Fig. 1 the view being along the line 2—2 of Fig. 1; and

25 Fig. 3 is a horizontal sectional view through a slightly modified form of furnace, having a single burner instead of a plurality of burners, the view being otherwise substantially the same as is Fig. 1.

30 The furnace shown herein as constituting a preferred embodiment of this invention is intended to be used primarily in the melting of iron, in malleable foundries and like places, and is particularly designed to 35 operate upon powdered coal as a fuel.

Powdered coal, as it is generally used, is 40 very finely ground, and in burning is admixed with air and introduced into the combustion space at high velocity. In the form 45 of furnace shown in Fig. 1 the combustion chamber 10 is provided with an arch or wall 11 which is inclined downwardly from one side of the furnace to the other, the material to be melted being placed upon the hearth 50 12.

55 Extending through the wall of the furnace, into the combustion space, at one side, and adjacent the higher side of the arch or top wall, are two burners 15, (in the modification shown in Figs. 1 and 2), each 60 of which is adapted for the burning of powdered fuel. The construction of the burner is immaterial so long as an efficient type of burner is used, and consequently 65 these burners are illustrated diagrammatically; but each of these burners should pref-

erably be inclined downwardly in the general direction of downward inclination of the arch.

The opening or passage 16, which connects the combustion space to the flue or 60 stack 17 is positioned at the same side of the combustion chamber as the burners. During operation the powdered fuel and combustion air are introduced under high velocity 65 through the burners 15, the burning gas and the hot products of combustion sweeping downwardly along the inclined arch or wall 11 and completely across the combustion space to impinge upon the opposite side wall whence they are diverted and turned 70 back as shown by the arrows in Figs. 1 and 2, sweeping across the material to be heated, and thence passing out through the opening 16 and the stack 17.

In Fig. 3 is shown a slightly modified 75 form of furnace in which only a single burner is provided, the stack in this case being connected to the combustion chamber at one end and the burner at the other, the hot 80 products of combustion sweeping across the combustion space and back—following substantially the course indicated by the arrows. In this form, also, the combustion chamber is tapered from the burner side 85 to the other side, as clearly shown in the drawing, this construction tending to further the circulation of the hot products of combustion.

But whether the furnace is provided with 90 one burner, or with a plurality of burners, the operation is substantially the same, the powdered coal burning within the combustion space, the hot products sweeping downwardly along the wall 11 and across the combustion space, and being diverted and 95 returned backwardly across the combustion space and out through the opening 16. As a result of this construction very efficient heating of the material upon the hearth 12 is secured.

100 While the forms of apparatus herein described constitute preferred embodiments of the invention, it is to be understood that the invention is not limited to these precise forms of apparatus, and that changes may 105 be made in either without departing from the scope of the invention which is defined in the appended claims.

What is claimed is:

110 1. A melting furnace of the character de-

scribed constructed for utilizing powdered fuel, comprising a combustion space, a hearth within said combustion space for supporting the material to be heated, an arch or top wall for said combustion space inclined downwardly from one side of the combustion space to the other, a plurality of burners for utilizing powdered fuel extending through the side wall of the furnace which is adjacent to the upper side of the inclined top wall, said burners extending into the combustion space, and being remotely positioned with respect to each other, and arranged to introduce substantially parallel streams of fuel into the combustion space, and a stack connected to the combustion space at the burner side thereof, and at the hearth level.

2. A melting furnace of the character described comprising a combustion space, a hearth therein for supporting the material to be heated, a top wall inclined downwardly across the said combustion space, two burners extending through one side wall of the furnace and opening into the combustion

space adjacent the higher side of the inclined top wall, and arranged to introduce substantially parallel streams of fuel into the combustion space, and a stack connected to the combustion space by means of an opening passing through the same side wall and opening into the combustion space between the two said burners.

3. A furnace of the character described comprising a combustion space, having the end walls thereof converging from the burner side to the other side, a hearth within said combustion space for receiving the material to be heated, an arch or top wall inclined downwardly from one side of the combustion space to the other, a fuel burner extending into the combustion space at one side thereof, and inclined downwardly in the general direction of downward inclination of the arch, and a stack connected to the said combustion space at the burner side thereof.

In testimony whereof I hereto affix my signature.

WILLIAM B. RUNYAN.
